(57) **CLAIM**

The ornamental design for a bottle for a birdfeeder, as shown and described.

DESCRIPTION

FIG. 1 is an isometric view of a bottle for a birdfeeder showing our new design.

FIG. 2 is a bottom perspective view thereof.

FIG. 3 is a side view thereof.

FIG. 4 is a top view thereof; and,

FIG. 5 is a bottom view thereof.

The broken lines in the Figures show portions of the birdfeeder that form no part of the claimed design.

The shade lines in the Figures show contour and do not claim surface ornamentation or treatment.
